Patented May 8, 1962

192,752

MACHINE FOR FILLING AND CLOSING INDIVIDUAL PACKAGES

Robert J. Aul, Toledo, Ohio, assignor to Multi-Fill Ma-
chine Company, Toledo, Ohio, a corporation of Ohio

Filed Apr. 10, 1961, Ser. No. 64,688

Term of patent 14 years

(Cl. D55—1)

II II III. II.

II II III. II.

FIG. 1.

FIG. 2.

FIG. 1 is a front perspective view of a machine for filling and closing individual packages showing my new design;

FIG. 2 is a front elevational view thereof;

FIG. 3 is a rear perspective view thereof;

FIG. 4 is an end elevational view thereof taken from the left side of FIG. 2; and

FIG. 5 is an end elevational view thereof taken from the right side of FIG. 2.

The broken line showing of the roll of wrapping mate-

rial and stack of packages in several of the drawing views is included for illustrative purposes only.

I claim:

The ornamental design for a machine for filling and closing individual packages, as shown and described.
